UNITED STATES PATENT OFFICE

DELL C. SNYDER, OF STONY RIDGE, OHIO

RAILWAY SWITCH

Application filed May 26, 1928. Serial No. 280,838.

This invention relates to a railway switch to divert a railroad train to a branch line, or to maintain connection with the main line. The object of the invention is to provide a movable switch, which will be less liable to damage in freezing weather by ice and to provide smooth joints at the switch ends. The two sides of the switch rails are held in relative relation by a plurality of transverse pivoted yokes, giving the two sides a true parallel motion. Each of the switch rails is provided with a hinge connection at the main line end and are guided over faces of parallel bolster plates having transverse grooves to divert sleet and water. At the switching end of the pivoted switch is mounted on the cross ties, a multiple-crank shaft connecting at a plurality of points with the switch yokes, and having a lever to throw the switch. A pivoted link connection with the crank-shaft gives the control lever control of the switch movement and simultaneously controls the movement of a semaphore to signal the engineer of an approaching train as to the condition of the switch setting.

The invention comprises a plurality of cooperating control features, which will be hereinafter fully described and the novelty of which will be specifically indicated in the appended claim.

In the accompanying drawings illustrating my invention:—

Figure 1 represents a plan of the invention—

Figure 2 is a like view of the switch when thrown to divert traffic to a branch line—

Figure 3 is a side elevation of the switch.

Figure 4 is a section on the plane 4—4 of Figure 3.

Figure 5 is a perspective view of a control spring for the switch.

Figure 6 is a section on the plane 6—6 of Fig. 8.

Figure 7 is a section on the plane 7—7 of Fig. 2.

Figure 8 is a transverse section on the plane 8—8 of Figure 1 and

Figure 9 is a perspective view of a bed plate or bolster to support the rails at the switch.

Referring now in detail to the drawing—
 1 represents the main line of a railway at which is mounted a switch 2 to throw the locomotive of a train direct along the main line, as indicated at Figure 1, or to divert it to a branch or side line as indicated in Figure 2. I provide both rails of the switch with a blunt end as indicated at 3 in Figure 1 to cooperate with the corresponding ends of the main or branch line rails. The switch rails 60 are of considerable length as I prefer to make them 16 feet in length and connect each switch rail by hinged joint, as indicated at 4, the hinged plates being bolted as indicated at 8, in the webs of the rails between the head and the base. A plurality of bolts thru the web as indicated at 7, clamp a spring plate 5 to the sides of the yielding spring joint. The plate 5 is slotted in one end as indicated at 6 to permit sufficient movement of the switch rails to divert traffic to the branch line. The switch rails are connected by a plurality of yokes 9, having a hinged connection 11, with a leaf of the hinge 11^a at each end of the yoke. This hinged connection permits the rails when thrown to move as a unit and to swing with a parallel motion to its proper position with relation to the main line rails or the branch line rails. The switch is thrown by a crank shaft controlled by a rightangled lever 15, forming an integral part of a crank shaft having a plurality of cranks 13, said shaft being mounted in chairs 14, spiked to the cross ties. A pair of pivoted guards 15^a on the cross tie act as a detent to hold the lever set when the switch is operated. An iron strap 16 is pivoted on the crank shaft and has a pivotal connection with the outside hinge leaf of the terminal yoke 9^a adjacent the switch.

The movable switch rails are guided over a pair of steel bolsters or bed plates 17, having a plurality of transverse webs 17^a forming depressions by which rain or sleet may be shed from the bed plates. Guide chairs are mounted at the sides of the bed plates and bolted to the cross ties, thus maintaining the main line beyond the switch in solid alignment or with the free ends of the switch rails 100 in the branch line, as indicated in Figure 7,

but the chairs 19 at the sides of the branch rails at their movable ends, are spaced transversely as indicated in Figures 1 and 2 to engage and clamp the edge of the rail when thrown in engagement with the main line or the branch line, respectively. A pivoted arm 10 on the same pivot as link 16 engages a pin projecting from a cylindrical semaphore 21 pivotally supported on the cross tie, the semaphore arms of which carry colors to indicate to an engineer the condition of the switch. For night use incandescent lamps may be mounted on the semaphore to indicate safety or danger—according to the direction in which the switch is thrown. The spring 10 side gives a bias to the switch and assists in preserving true alinement of the switch rails when set for connection with the main line. When thrown over to connect up with the branch line, the cranks 13 will be on dead center and will prevent any accidental displacement. A similar lock will of course occur when the crank is thrown for connection with the main line. The transverse grooved surface of the bed plate permits thorough drainage of water away from the switch and prevents the accumulation of ice to interfere with the hand control switch, thereby preventing the rails at the switch freezing fast to the bed plate and preventing their shifting to the branch line on emergency. The bed plate has at each end a plurality of spike holes 18 by which it may be spiked to the cross ties, while extending beneath the end 25 of the main line rails at each end. At the movable end of the switch the bed plate is sufficiently wide to bridge the rails of the main and branch lines, as will be clear from an inspection of Figures 1 and 2.

Having thus described my invention, what is claimed as new and desired to secure by Letters Patent, is:—

In a railway switch, fixed rail sections, laterally movable rail sections, means connecting the movable rail sections to provide for simultaneous movement, pivotally connected hinge plates secured to one side and hingedly connecting the adjacent ends of the fixed rail sections and the laterally movable rail sections, and resilient plates upon opposite sides of and connecting the fixed and movable rail sections, each of said resilient plates having a sliding connection with at least one rail section.

In testimony whereof I affix my signature.
DELL C. SNYDER.
